FIG. 1 is a top perspective view of the claimed design in accordance with one aspect of the current disclosure.

FIG. 2 is a front elevation view thereof.

FIG. 3 is a rear elevation view thereof.

FIG. 4 is a top plan view thereof.

FIG. 5 is a bottom plan view thereof.

FIG. 6 is a left-side elevation view thereof; and,

FIG. 7 is a right-side elevation view thereof.

The invention pertains to an ornamental design for a measurement device with multiple fixed distances. The solid lines represent the bounds of the claimed design, whereas those features shown in broken lines, including each upper surface and a base surface of the measurement device with multiple fixed distances, form no part of the claimed design.
